UNITED STATES PATENT OFFICE

WILLIAM R. GRUBER, OF NEW YORK, N. Y., ASSIGNOR TO "HEALTH" RAY MFG. CO. INC., OF NEW YORK, N. Y., A CORPORATION OF NEW YORK

DESIGN FOR AN ARC LAMP

Application filed February 6, 1931. Serial No. 38,575. Term of patent 14 years.

To all whom it may concern:

Be it known that I, WILLIAM R. GRUBER, a citizen of the United States, residing at New York, in the county of Bronx and State of New York, have invented a new, original, and ornamental Design for an Arc Lamp, of which the following is a specification, reference being had to the accompanying drawings, forming part thereof.

Fig. 1 is a perspective view of an arc lamp, intended for use as a flashlight for photo-

graphic purposes, provided with adjustable reflector walls shown in open position and reposing upon a removable stand, and

Fig. 2 is a perspective view of the device seen from the rear end thereof.

I claim:

The ornamental design for an arc lamp, as shown and described.

In testimony whereof I herewith affix my signature.

WILLIAM R. GRUBER.
